US00D824856S

(12) **United States Design Patent** (10) Patent No.: **US D824,856 S**
Corona (45) Date of Patent: ** *Aug. 7, 2018

(54) **STRAIGHT FEMALE ELECTRICAL CONNECTOR WITH LOCKING ARM**

(71) Applicant: **DSM&T Company, Inc.**, Fontana, CA (US)

(72) Inventor: **Sergio Corona**, Upland, CA (US)

(73) Assignee: **DSM&T Company, Inc.**, Fontana, CA (US)

(*) Notice: This patent is subject to a terminal disclaimer.

(**) Term: **15 Years**

(21) Appl. No.: **29/598,115**

(22) Filed: **Mar. 23, 2017**

(51) LOC (11) Cl. **13-03**

(52) U.S. Cl.

USPC **D13/146**; D13/149

(57) **CLAIM**

The ornamental design for a straight female electrical connector with locking arm, as shown and described.

DESCRIPTION

FIG. 1 is a top, front, right side perspective view of my new design of a straight female electrical connector with locking arm.

FIG. 2 is a right side elevational view thereof.

FIG. 3 is a left side elevational view thereof.

FIG. 4 is a top plan view thereof.

FIG. 5 is a bottom plan view thereof.

FIG. 6 is a front side elevational view thereof; and,

FIG. 7 is a rear side elevational view thereof.

The broken lines in FIGS. 1, 6 and 7 represent environment only, and form no part of the claimed design.

1 Claim, 2 Drawing Sheets
